UNITED STATES PATENT OFFICE.

MARTIN V. B. EUANS, OF CIRCLEVILLE, OHIO.

SASH-HOLDER.

SPECIFICATION forming part of Letters Patent No. 374,867, dated December 13, 1887.

Application filed December 10, 1885. Serial No. 185,300. (No model.)

To all whom it may concern:

Be it known that I, MARTIN V. B. EUANS, a citizen of the United States of America, residing at Circleville, in the county of Pickaway 5 and State of Ohio, have invented certain new and useful Improvements in Sash-Holders; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 My invention relates to certain new and useful improvements in sash-holders; and it consists in combining with a spring-holder having a cork roller a strip of flexible material, which is attached to the sash or window-frame 20 so that the roller will bear upon the same and hold the sash in any position in which it may be placed without the use of weights, as will be hereinafter fully set forth, and specifically pointed out in the claim.

25 In the accompanying drawings, which illustrate my invention, Figure 1 is a perspective view of a window sash and frame, showing my improvement applied thereto. Fig. 2 is a vertical sectional view. Fig. 3 is a transverse 30 sectional view, and Fig. 4 is a detail perspective view.

A refers to the window-frame, which is of ordinary construction, and has secured thereto (by any suitable means, as pins or staples) be- 35 tween the sash guide-rails a strip of compressible material, as rubber, said strip being indicated by a.

B refers to a metallic casing or casting, the central portion of which is semicircular in out- 40 line, and which is provided with perforated end pieces, b, through which pass wood-screws for securing the same within recesses therefor in the sash-frame. This casing B has side walls, c, each of which is provided with a horizontal slot, c', within which plays the journal of the compressible or flexible roller D, said roller being made of cork, for the reason that it is provided naturally with numerous small open- 45 ings, which will provide ventilating-spaces,

thus preventing the rubber strips heating or 50 adhering to the same when said roller remains for a long time in one position. The inner portion of the metallic casing, which lies within the recess in the sash, is provided with a recess, d, within which will lie one end of a 55 spiral spring, the opposite end of said spiral spring bearing upon the flat portion of a roller-frame, E, said roller-frame having its sides e bent at right angles and perforated for the reception of the journal F, which passes 60 through said perforations and into the slot c', formed in the side wall, c, of the casing. The sides e of the roller-frame adjacent to the journal F are provided with projecting lugs e', which lie within the slots c' and serve as guides 65 for the roller, thus limiting said roller to play directly in and out of the casing. The casing may be attached to the window-frame and the strips to the sash, or vice versa, the operation in each case being the same, and any suitable 70 number of casings may be applied thereto, according to the weight of the sash.

By employing the device herein described, sash-weights and other attachments may be entirely dispensed with, the pressure of the 75 roller upon the flexible strip being sufficient to hold the sash in any position in which it may be placed, and said spring-pressure will also prevent the sashes rattling.

I claim—

80 The combination, with a window-frame and its sash, of sash-holders seated in opposite sides of the frame, each consisting of a casing having slotted side walls and a recess at the back, a roller-frame provided on each side 85 with guide-lugs, a spring seated at its inner end in the recess of the casing and pressing outward on the roller-frame, a spindle journaled in the roller-frame and carrying a roller of porous yielding material, and a strip of 90 rubber secured at each side of the sash opposite the sash-holder, substantially as described.

In testimony whereof I affix my signature in presence of two witnesses.

MARTIN V. B. EUANS.
